UNITED STATES PATENT OFFICE.

PEARL B. WOODRUFF, OF HUMESTON, IOWA.

ENGINE SUPPORT AND CRANK CASE.

Application filed July 25, 1921. Serial No. 487,533.

To all whom it may concern:

Be it known that I, PEARL B. WOODRUFF, a citizen of the United States, and a resident of Humeston, in the county of Wayne and 5 State of Iowa, have invented a certain new and useful Engine Support and Crank Case, of which the following is a specification.

The object of my invention is to provide an engine support and crank case of very 10 simple, durable and inexpensive construction.

A further object is to provide a device of the kind mentioned, having a portion adapted to be mounted on the main frame of a 15 motor vehicle chassis and to conveniently support in a rigid manner the motor, and to provide in connection therewith a detachable member, which serves as a crank transmission and fly-wheel case.

20 More particularly, it is my object to provide such a device, which is so constructed and arranged as to facilitate access to the parts of the engine for purposes of repair and replacement.

25 With these and other objects in view, my invention consists in the construction, arrangement and combination of the various parts of my device whereby the objects contemplated are attained, as hereinafter more 30 fully set forth, pointed out in my claim, and illustrated in the accompanying drawings, in which:

Figure 1 shows a side elevation of an engine support and crank case with an engine 35 or motor mounted thereon.

Figure 2 shows a vertical, transverse, sectional view taken on the line 2—2 of Figure 1, illustrating the connection between my device and the motor and also the method 40 of hanging my device on the main frame.

Figure 3 is a detail, sectional view taken on the line 3—3 of Figure 1; and

Figure 4 shows a top or plan view of the engine support part of my structure.

45 In the accompanying drawings, I have used the reference numeral 10 to indicate generally the cylinder block of an automobile engine, such for instance as the ordinary Ford engine.

50 The cylinder block of an engine of this type is ordinarily mounted directly on the crank case and the crank case is mounted on the frame of the chassis.

The ordinary crank case has a plate on its 55 under surface, which is removable to permit access to the connecting rod bearings.

The old structure just mentioned has certain serious defects in that with such a structure, it is very difficult to get proper access to the engine parts for purposes of repair or 60 replacement.

With the old structure, it is impossible to repair the main bearings without entirely removing the motor from the car.

In my device, I have provided an engine 65 support element, which comprises opposite spaced side members 11 arranged substantially parallel with each other and having the form of outwardly opening channel bars. At their forward ends, the members 11 are 70 slightly inclined toward each other, as at 12, and are connected with a small casing 13 for the fan pulley.

The casing 13 supports at its forward end the front engine hanger 14. The hanger 14 75 projects forwardly from the casing 13, so that it may be supported on the transverse frame member 15. At their rear ends, the frame members 11 are inclined outwardly 80 away from each other, as at 16, thence rearwardly as at 17, thence toward each other as at 18 and thence rearwardly as at 19. The portions 16, 17, 18 and 19 have the channel bar shape.

The portions 17 are supported on the main 85 frame members 20 of the chassis by means of hangers 21. Each hanger 21 may have an outwardly, opening channel-shaped member 22, having at its outer upward portion, an upwardly inclined upper member 23 terminating in a lateral extension 24, which rests on the main frame member 20 and is bolted thereto, as at 25. A bolt 26 is extended through the main frame 20 and the hanger 21 as shown in Figure 3. 95

The motor 10 has a flange 26, which sets upon the upper flange of the support 11, as shown in Figure 1, and is bolted thereto by bolts 27. The upper half of the fly-wheel and transmission case 28 has a flange 29, 100 which rests upon the upper flanges of the members 16, 17, 18 and 19, as shown in Figure 1, and is bolted thereto by bolts 30.

I provide in connection with this part just described, a crank case 31 having a fly-wheel portion 32 and a transmission portion 33. The crank case is provided with a flange 34, which is bolted to the lower flange of the member 18 by means of bolts 35. 105

Detachably fastened to the bottom of the 110 crank case 31 is a removable plate 36.

It will be seen that in the practical use of

my improved device; the engine is supported on the support 11, and the support 11 is supported on the main frame, as shown at the left-hand of Figure 1 and in Figure 3.

5 In order to give added strength to the support 11, the edges of its flanges are inclined toward each other, as shown at 37 in Figure 2.

It will be seen that by the construction 10 above described, I have provided a strong and rigid support for the engine and a proper support for the crank case. The crank case is so mounted on the support 11 that the entire crank case may be readily 15 removed for permitting access to the motor parts, especially the cylinders and connecting rods and also to the fly-wheel and transmission.

It will be noted that the support 11, having 20 its members connected as shown and as especially illustrated in Figure 4 forms a unit, which can be conveniently packed, transported, installed or disassembled. It is an unit which can be easily and readily 25 mounted on the frame of the car and upon which the engine can be easily and rigidly supported and connected.

It may be mentioned that the hand crank extends through the member 14 for engagement with the front end of the engine shaft.

It should be mentioned perhaps that the

casing 13 which extends below the fan pulley has at its rear end a partition 40, as shown particularly in Figure 4.

Some changes may be made in the details 35 of the construction and arrangement of the various parts of my improved device without departing from the real spirit and purpose of my invention, and it is my intention to cover by my claim, any modified forms 40 of structure or use of mechanical equivalents, which may be reasonably included within its scope.

I claim as my invention:

In a device of the class described, the combination of a motor frame member, a supporting device mounted thereon, comprising spaced outwardly opening channel-shaped members, a casing or receiving element at the forward ends of said last members, an 50 engine supported on said supporting device members, a fly wheel and transmission cover casing supported on other parts of said members, a crank case having fly wheel and transmission case portions supported on the 55 lower flanges of said supporting members, a hanger at one end of said first-named casing, spaced hangers secured to said supporting members near the other ends and to the chassis frame members.

Des Moines, Iowa, July 16, 1921.

PEARL B. WOODRUFF.
